UNITED STATES PATENT OFFICE.

ALFRED OTTO HERMANN PETERSEN, OF ALTONA ELBE, GERMANY, ASSIGNOR TO N. V. NEDERLANDSCHE INSTALLATIE MAATSCHAPPIJ THERMA, OF AMSTERDAM, NETHERLANDS.

CONDENSING APPARATUS.

Application filed May 20, 1925, Serial No. 31,526, and in Germany January 17, 1924.

When hot solutions evaporate in vacuo in a continuous operation for the purpose of cooling, condensing or separating salts, the condensates are usually withdrawn by 5 means of a jet pump. If a water jet pump is used as the jet pump, then the quantity of water to be used in operation must be large in order to carry away and volatilize the vapors which are produced.

10 The subject of the present invention resides in effecting the removal of the condensate with at the most so much water as is necessary for the condensation, as the condensates before passing into the jet pump, are condensed by a condenser of usual construction by the water of the jet pump. In this connection it is immaterial for the carrying out 15 of the invention whether the pump is driven by the cooling water which is flowing in or flowing out.

The invention is particularly applicable for the separation of epsom salts (Glauber salt) and potassium salts. For the purpose of obtaining a high degree of vacuum 20 and therefore a low cooling temperature the condenser or the jet pump can also be operated with cooled water or cooled brine.

In the drawing is shown by way of example a device for carrying out the inven-

tion. The hot solution enters the evaporator *a* at *b*, is evaporated in the vacuum, is thus cooled, and is carried away through the pipe *c* together with any salts that may have been separated. The vapors which are formed are conducted by the pipe *d* into the 35 condenser *e*, condensed in the known manner by cooling water and removed as condensate by means of the jet pump *f*.

Having thus described my invention, what I claim as new and desire to secure by Letters Patent is:—

1. In combination, a condenser, and a jet pump connected to said condenser for removing condensate therefrom, said jet pump being operated by the cooling water passed 45 through said condenser.

2. In combination, a condenser which vapors are condensed, an inlet for the admission of cooling water at one end of said condenser, an outlet pipe at the other end 50 of the condenser, and a jet pump connected to said outlet pipe for removing condensate from said condenser and operated by the cooling water of said condenser flowing through said outlet pipe.

In witness whereof I hereunto subscribe my name this 29th day of April, A. D. 1925.

ALFRED OTTO HERMANN PETERSEN.
